UNITED STATES PATENT OFFICE.

ALEXANDER E. SORUM, OF TERRE HAUTE, INDIANA, ASSIGNEE, BY MESNE ASSIGNMENTS, TO REMINGTON ARMS COMPANY, INC., OF NEW YORK, N. Y., A CORPORATION OF DELAWARE.

ADDING AND AMOUNT DENOMINALIZING MACHINE.

Application filed August 8, 1914. Serial No. 854,837.

10 The operation of making up the payroll of an institution, factory, or store having many employees, is at the present time a tedious and exacting one notwithstanding that the introduction of the adding machine has rendered the problem of accurately setting up the various items going to make up the payroll comparatively simple.

20 After a payroll is made up it is necessary to procure from the bank ordinarily a sum of money equivalent to the total of the wages represented by the payroll and the object of this invention is to provide a machine for facilitating the determination of the number 25 of bills and coins required in order to pay the entire amount of the payroll, a certain number of bills or coins or both being allowed for each individual item of the roll. In other words, the machine of this invention is capable of mechanically determining how many units of different denominations of money are required to make up a given amount within the maximum which the machine is designed to handle. Thus if a payroll or other item amounts to ten dollars and fifty cents, by the operation of certain manipulative devices and counting mechanism of the machine the counters provided may be caused to separate the said amount into denominational divisions, so to speak, indicating that one ten dollar bill and one fifty cent piece are required to cover the amount of the item.

30 Still another object of the present invention has been to so combine with an adding machine, counting instrumentalities whereby the foregoing object may be accomplished, the keyboard of the adding machine being advantageously utilized as the controlling means for the various counting devices one of which is provided for each denomination of money of the particular system in connection with which the machine is used. With this in view, by comparatively slight alteration the machine hereinafter set forth may be adapted to denominationalize amounts of money, or the like, of different monetary systems.

35 Still another object especially had in view in the carrying out of the present invention has been to so combine an adding machine and counting instrumentalities as to permit of the independent operation of the adding machine in respect to said instrumentalities,

this being accomplished by the utilization of 55 means to render inoperative the counting devices so that the adding machine may be employed alone for the purposes for which it is commonly used.

40 The counting mechanism of this invention 60 has been designed with a special view to compactness, a number of sets of counting devices being controlled by a single controlling member though independently operable through the medium of the manipulative devices of the keyboard and a main actuator of manual or motor driven type as the case 65 may be.

45 With the above and other objects in view, this invention consists in the construction, 70 combination and arrangement of parts all as hereinafter more fully described, claimed and illustrated in the accompanying drawings, wherein:

50 Figure 1 is a plan view of a machine embodying the invention, same being broken away at its intermediate portion.

55 Figure 2 is a fragmentary view in front elevation showing more particularly two of the denominational counters and resetting 80 means therefor, certain wheels of one of the counters being illustrated in section.

60 Figure 3 is a sectional view through the keyboard section of the machine transversely of the latter.

65 Figure 4 is a transverse sectional view through the counting section of the machine.

70 Figure 5 is a side view showing more particularly the controlling devices of the adding machine, and main actuator.

75 Figure 6 is a front elevation of the removable plate carrying the counters and resetting mechanism therefor, certain of the counters being shown and others omitted.

80 Figure 7 is a fragmentary bottom plan view of the parts shown in Figure 6.

85 Figure 8 is an end view of the same showing clearly the locking member for the resetting shaft.

90 Figure 9 is a sectional view taken about on the line 9—9 of Figure 6.

95 Figure 10 is a view similar to Figure 9 taken about on the line 10—10 of Figure 6 and showing additionally the means for supporting the front plate and counting mechanism thereon, on the frame of the machine.

100 Figure 11 is an enlarged detail bringing

out more clearly the locking means for the resetting shaft.

Figure 12 is a combined view showing details of the transfer mechanism intermediate 5 the wheels of each counting device, the transfer pawl being as when in process of carry-over and also in its normal position.

Figure 13 is a top plan view partly in section and broken away, showing more particularly the means for disabling the counter mechanism.

Figure 14 is a vertical sectional view of the same.

Figure 15 is a front view showing the 15 counting section partly broken away and in front elevation, the adding section being illustrated in vertical section.

Figure 16 is a detail view of one of the friction springs carried by the counter shaft.

20 General structure of machine.

As seen clearly in Figure 1 of the drawings, the machine of this invention may be said to comprise an adding section A and a 25 counting section B, the counting devices being located at the front of the latter section and consisting of a number of individual counters or registers suitably arranged beneath a casing plate C apertured at intervals 30 so that the numbers of the counting wheels of said devices may be seen during and after the operation of the same. The adding section A of the machine is for all practical purposes a complete adding machine of itself, being constructed substantially in accordance with the adding machine embodied in the copending application of Nelson White, Serial Number 755,817, filed March 20, 1913, reference being made 35 to said application for details of said machine which will not be fully presented hereinafter, being non-essential to the peculiar novelty of the present invention.

40 The adding section.

As is usual, the adding machine forming the adding section of this combined machine includes a keyboard having a plurality of rows of keys 29, each row preferably 50 nine in number and the capacity of the machine susceptible of change merely by using a larger or smaller number of rows of keys and corresponding cooperative parts. As seen in Figure 3, each key 29 of a 55 row is formed with an inclined slot receiving a stud 92 of an indexing plate 90, the several plates 90 for each row of keys 29 being superposed and supported by any conventional means to slide longitudinally 60 and horizontally to and fro so that by the depression of any one of the keys 29 its associated plate 90 will be projected at the front end into the path of movement of a projection 80' of the adding rack 80, one of 65 which is provided for each row. The plates

90 differentially limit the movement of the adding rack 80 with which they cooperate, allowing from one to nine increments of movement for said rack for setting up predetermined amounts by the adding wheels 70 75 87 included in the accumulating mechanism at the front of the adding section A. The teeth of the adding rack 80 are of course adapted to engage and be disengaged from the pinions 84 of the adding wheels, as controlled by the ordinary operation of the machine, and totalizing means disclosed fully in the application herein referred to. The excursions of the adding racks 80 control the movement of the type carriers 95, in the well known manner, levers 75 being connected at their front ends with the adding racks 80 and at their rear ends with said type carriers 95. A main actuator including the handle 38 (see Figures 1 and 5) and the shaft 39, is provided and is operable to raise the cam slotted arms 69 and the transverse detent members 73 and 74 carried by the latter, thereby releasing the levers 75 from the detaining action of the part 74 and permitting certain springs 76 to actuate the levers 75 so that predetermined adding racks will move downwards, and the type carriers will be elevated so that their type are brought to the printing point under the control of the indexing plates 90. At a suitable period in the operation of the main actuator handle 38 the hammers 171 will be fired, causing the amount set up by the depression of the keys 29 to be recorded as usual, the said amount being accumulated by the adding wheels in the customary manner.

70 The counting section. (Selectors and actuators.)

In the counting section of the machine are mounted a number of series of horizontal selectors 20 (see Figures 3, 4 and 15), there being one series of selectors for each set of keys disposed transversely of the keyboard or longitudinally of the whole machine. The selectors 20 are downwardly compressible, being normally upraised by springs 26 connected thereto intermediate their ends, and said selectors extend into the 110 keyboard or adding section of the machine beneath the lower ends of the keys of the latter and have projections 28 directly engageable by said keys when depressed. Thus it is that each key 29 is adapted to engage and depress one or several of the selectors 20 whereby to cause hooks 48 on the right hand ends of said selectors to be engageable by a bail 47 mounted upon a rock shaft 46 near the right hand end of the machine. The shaft 46 is rocked on each operation of the handle 38 owing to the provision of a cam 40 movable with the shaft 39 (see Figure 5), said cam engaging a roller 41 of a lever 42 pivotally supported inter- 115 120 125 130

mediate its ends. The lever 42 is connected by a link 44 with an arm 45 on the shaft 46 and rocking of the shaft 46 by movement of the handle 38 will cause swinging of the bail 47 in such a way that if the hooks 48 of any of the selectors 20 have been engaged with the bail, a longitudinal movement will be imparted to said selectors for a purpose to be now described.

10 It is contemplated to utilize the selectors 20 to select for operation the actuators of the counting devices at the front portion of the counting section B of the machine. The said actuators consist of longitudinally slidable bars 3 (see Figures 1 and 4) each bar being susceptible of slight lateral movement at its rear end whereby a pin 3' carried by said end may be interlocked with an adjacent arm 11 of the counter actuating shaft 12. Any suitable means may be provided intermediate the selectors 20 and the counter actuators 3 whereby each selector is adapted to actuate or set one or more of the actuators 3 into positions in which they are connected with the cooperative arms 11 and thus rendered operable to cause corresponding operation of the counting device associated with each predetermined actuator 3. The preferred means aforesaid comprises projections 21 on the selectors 20 adapted to engage and swing bails 22, pivoted at 22', said bails having lever arms 22" engaging at their lower ends with members 3 whereby to shift the actuators 3 into and out of interlocking relation with respect to their arms 11.

The counters.

As above premised, it is contemplated to employ a counter for each actuator 3, said counter being supported by a plate 201 (see Figure 10 especially), which plate is detachably mounted at the front portion of the counting section B. Preferably the plate 201 has inwardly projecting hooks 202 at the lower portion of its opposite ends, same capable of engaging over a supporting rod 203. In like manner other hooks 204 are carried by the upper ends of the plate 201 and are adapted to be engaged by hooks of arms 205 carried by a shaft 206 suitably supported on the frame of the machine, said shaft to be key-operated or otherwise controlled so as to eliminate likelihood of unauthorized removal of the counting devices from the machine. The plate 201 is provided with a plurality of openings at its lower portion through each of which one of the counter actuators 3 is adapted to operate, the front end of the actuator being engageable with a lug 207 on a slide 208. The counting devices for each of the actuators 3 are substantially alike and therefore only one will be described in detail, same including the slide 208 previously mentioned having its lug 207 and said slide being supported

by a bracket 209 fastened to the plate 201. The slide 208 has a vertical lug 208' provided with a lateral pin 208" which enters the bifurcation of an extension 210 of a disk 211 mounted on the resetting shaft 212. At one side of the disk 211 are the several counting wheels 213 which may be styled the usual units, tens, hundreds and thousands wheels, the number of these wheels being adapted to be increased according to the requirements. The disk 211 carries at one side thereof the pawls 214 pressed outwardly by spring means as at 215, said pawls engaging with teeth 216 formed internally on the units wheel 213. It is to be understood that the disk 211 and the counting wheels are coaxially mounted loose on the resetting shaft 212 and there is provided between each counting wheel 213 and its next adjacent counting wheel a suitable carryover mechanism such as illustrated in Figure 12. This transfer mechanism is substantially the same as that of United States Patent No. 728,502 issued May 19, 1903, to W. L. Sandage and no claim is therefore made to the mechanism as shown therein. As seen in Figure 12, however, the units wheel 213 has pivoted thereto a transfer pawl 213' which when the nose thereof engages a projection 217 and the tail thereof is received in a recess 218, interlocks the units wheel 213 with the tens wheel 213 at its side, the tens wheel having projections or teeth 219 on its inner periphery adapted to be engaged by the pawl 213' when so adjusted. The projection 217 is in the nature of a cam, being formed on a collar 220 keyed or otherwise fixed on the resetting shaft 212. Obviously at one time during each revolution of the units wheel 213, the pawl 213' thereof, which is housed in the recessed side of the tens wheel, is caused to move outwards at its nose into engagement with the teeth 218 of the wheel 213 of higher denomination, whereupon the increment of movement imparted to the units wheel or wheel of lower denomination at this time is likewise imparted to the wheel of higher denomination because the two are temporarily interlocked during one-tenth portion of their revolution, in an obvious manner. When this increment of movement happening at the time of transfer, is ended, the tail of the pawl 213' rides out of the recess 218 and disengages the pawl of the counting wheel of lower denomination from the wheel of higher denomination in an obvious manner. The specific mode of transfer or carryover above described is immaterial to this invention because it is contemplated to use any desirable type of carryover for the counting wheels of each counting device, the wheels of all of said devices being carried by the common shaft 212, the latter forming not only the axis for the counting wheels but also a resetting means.

Every time one of the actuators 3 is operated its outer end engages the slide 208, thereby moving the latter outwards against the tension of a spring 219. At the same time the connection of the slide 208 with the disk 211 partly rotates the latter and such movement is correspondingly imparted to the units wheel of the counting device, the movement being transferred to the wheels of higher denominations in the customary manner above explained.

Counter resetting mechanism.

As clearly shown by Figure 6 of the drawings, the counting wheels of all of the counting devices carried by the plate 201 are mounted upon the common resetting shaft 212. Each counting device comprises as its main parts the counting wheels 213 referred to, the disk 211 for each set of wheels and the spring retracted slide 208 interlocked with said disk. Assuming that the manipulative keys 29 have been operated through a series of transactions of the machine and it is desired to normalize the various counting devices, the operator will depress the finger piece 220 of a locking lever 221 which is mounted on a locking shaft 222 and formed with a lug 223 adapted to engage in a notch 224 formed in the locking wheel 225 rigidly secured to the shaft 212. The depression of said lever 221 which is normally held by a spring 226 in locking engagement with the wheel 225, does two things. First the shaft 222 is rocked with the lever as the lug 223 is disengaged from the notch 224, and the wheel 225 and the shaft 212 are released and free to rotate in the brackets 227 supported by said shaft on the plate 201. The shaft 222 not only carries the locking lever 221 at one end but at the other end an arm 228 is mounted, the said arm 228 and the lever 221 having inwardly extending studs 229 projecting beneath a resetting member 230 or plate 230. The resetting member or plate 230 extends lengthwise of the main supporting plate 201 and is formed with a flange 230' adapted to engage with resetting lugs 231 one of which is provided on the peripheral portion of each counting wheel. In other words, under normal conditions there is hung on the shaft 222 a resetting plate having a spring 232 connected therewith and with the locking lever 221 (see Figure 8), said spring tending to move the flange 230' of the resetting plate in engagement with the resetting or zeroizing lugs 231 of the counting wheels. However, normally the spring 226 connected with the lever 221 is of greater tension than the spring 232 and thus when the lever 221 interlocks with the locking wheel 225, the pins 229 carried by the lever 221 and by the arm 228, bear against the under side of the resetting plate and hold the latter in a position in which it cannot

engage with the zeroizing lugs 231. The depression of the locking lever 221, however, moves said lever to disengage it from the locking wheel 225 and simultaneously the shaft 222 is rocked to permit of very slight downward movement of the resetting plate 230 and its flange 230' so that the flange 230' is in the path of rotation of the lugs 231 and when the resetting shaft 212 is turned by the knurled knob or handle 233, the various counting wheels of the several counting devices will be zeroized owing to the engagement of the lugs 231 with the flange of the resetting plate 230. At this particular time the notch 224 will be again opposite the locking lug 223 and the latter will spring into the notch under the action of the spring 226 normalizing the locking lever 221, locking the shaft 212, and rocking the shaft 212 sufficiently to cause the pins 229 of the parts 221 and 228 to raise the resetting plate into a position wherein its flange 230' is out of the path of rotation of the lugs 231.

Main actuator connection to counter actuating shaft.

As seen in Figures 13 and 14, the actuating shaft 12 which carries the arms 11 capable of being interlocked with the actuators 3, is provided with an arm 63 having a hook 64 engaging normally a stud 66 on the vertical rocker arm 56. The rocker arm 56 is carried by a shaft 55 which also has a forwardly extending arm 54 bifurcated at its front end 54' so as to engage a stud 53 on an angular lever 49 which is mounted on the main actuating or handle shaft 39, a spring 50 tending to pull the rear arm of the lever 49 downwards. Having in view the foregoing it will be apparent that as the handle 38 is pulled forwards the shaft 39 and lever 49 are rocked, thus raising the arm 54 and pulling the arm 56 rearwards. The movement of the arm 56 is communicated through the hook 64 to the arm 63 and to the shaft 12 having said arm, whereby the several arms 11 on the shaft 12 will be rocked every time the handle 38 is moved. Those of the actuators 3 interlocked with the arms 11 will be correspondingly actuated during the movement of the arms 11.

Complete operation of adding and computing machine.

Assuming that it is desired to ascertain how many units of different denominations of money are required to make up the value of a predetermined amount, and it being understood that for each denomination of money there is provided at least one of the actuators 3 and a corresponding counting device comprising a set of counting wheels 213, the operator will set up the amount of money or item on the keyboard of the adding section A in the usual way. This

is done by depressing the keys 29 which when set will control the differential movement of the adding racks 80 that are adapted to be unlocked owing to the shifting of certain locking bars 88, one of which is operable by the keys of each row. The differential movement of the type carriers 95 is also, of course, controlled by the setting of the keys 29. Certain of the selectors 20 will be depressed by the keys by which the amount is set up on the keyboard and these particular selectors are thus moved downwards so that their hooks 48 engage over the bail 47. The handle 38 is now pulled forwards and its first effect is to actuate the bail 47 pulling the depressed selectors 20 longitudinally and causing these selectors to move the actuators 3 with which they are connected into interlocking engagement with the corresponding arms 11 of the actuating shaft 12. The shaft 12 is not immediately rocked by the forward movement of the handle 38 because of the play of the stud 66 in the hook 64 (see Figure 14), but just as soon as the selectors 20 have been pulled longitudinally in the manner indicated, setting their actuators 3 properly, the hook 64 acts on the arm 63 to rock the said arm and the shaft 12, the several arms 11 of the latter meanwhile interlocked with actuators 3, causing said actuators to move outwards longitudinally to impart movement to the slides 208 of predetermined counting devices. If the amount to be set up on the machine is twenty-five dollars and fifteen cents, for instance, the key 29 designated 2 in the fourth row from the right (Figure 1) will be depressed, as will also be the keys 29, designated 5, 1 and 5 of the third, second and first rows respectively. There is at least one counting device for pennies, one for nickels, one for dimes, one for quarters, and so on up with respect to the larger denominations of money. So, the depression of the key 29 designated 2 of the fourth row, above mentioned, will control the twenty dollar selector 20, its actuator 3 and the associated counting device will be given one increment of movement when the handle 38 is operated. In like manner the counting devices for the five dollar selector 20 and its actuator 3, the ten cent selector 20 and its actuator 3, and the five cent selector 20 and its actuator 3, will be each given one increment of movement on the operation of the handle 38. The respective counting devices or registers above referred to will be set with the number 1 of unit wheels 213 exposed, at the conclusion of a transaction setting up the amount mentioned.

If a transaction to the amount of ninety cents be set up on the machine, incidental to the depression of the key indicated 9 of the tens row of keys 29, said key will depress one of the selectors 20 having four

projections 21. Such selector 20 is interlocked by the depression of the key with the selector bail 47 and on the initial pull on the handle 38 the selector 20 is moved longitudinally toward the right end of the machine 70 and its four projections 21 shift four of the bails 22. The particular bails 22 which are thus actuated shift four actuators 3 into interlocking connection with the arms 11 of the actuator shaft 12. The said four actuators cooperate with the counters or registers for fifty cent pieces, twenty-five cent pieces, dimes and nickels, and the final operation causes such actuation of the actuators 3 that the fifty cent counter, twenty-five cent counter, dime counter and nickel counter are each given one increment of movement, thereby registering up the several denominations of money that will be required to make up the transaction of 85 ninety cents.

While in Figure 9 the slide 208 is shown to have a single lug 207, the corresponding slide shown in Figure 10 is formed with two of these lugs. The object of this is to permit 90 of the employment of two of the actuators 3 one alongside the other, one capable of engaging the innermost lug of the construction in Figure 10 whereby two increments of movement may be imparted to the slide 95 208, or the actuator engaging the outermost lug capable of imparting only a single increment of movement to the slide. Of course the movement of the units counting wheel 213 corresponds to the amount of 100 movement imparted to the slide 208 cooperating therewith. Thus if the amount set up in the machine be forty dollars it is possible by having an extra actuator 3 for the twenty dollar counter, to adjust the latter 105 to give two increments of movement to the slide 208, setting the counter accordingly and thus indicating that two twenty dollar bills or twenty dollar gold pieces from the denominational standpoint are necessary to make up the amount of the transaction set up in the machine. While at least one counter is provided for each denomination of currency of the particular monetary system in connection with which the machine is used, as matter of fact, in reference to United States money it would be preferable to provide two counting devices for the counting of pennies, and two counting devices for the counting of dimes. When 110 one cent is set up on the machine one of the actuators 3 for one of the penny counters will be actuated to set the counter one increment of movement. If two cents be set up both of the actuators 3 of one of the penny 115 counters may be actuated to set up two cents by the two increments of movement of the units counting wheel. If three cents is to be set up the two actuators of one of the counters, and one actuator of the other counter 120 125 130

for the pennies, may be rendered operable to correspondingly set the counters on the movement of the handle 38.

5. *Disabling means for counting mechanism.*

Under certain conditions when it is not necessary to employ the counting mechanism of the counting section B, that is, for instance, when the adding section A is being used as an ordinary adding machine, it is desirable that operation of the counters be discontinued. This is readily effected by the provision, as seen in Figures 12 and 13, of a "no count key" 61 that is adapted to be depressed and held depressed by a notch 61' therein engaging the top plate of the keyboard of section A. When key 61 is depressed against the tension of the spring 62 the lower end of the key has an offstanding pin 60 which engages a lever 58 pivoted to the frame of the machine. The lever 58 is adapted to move an arm 58' fixed on its axis 58" and the arm 58' is adapted to abut with the hook 64 and force the latter downwardly against the action of a spring 65, holding the hook disengaged from the stud 66 so long as the key 61 remains down. Under these conditions it is obvious that in the transactions of the accumulating instrumentalities since the hook 64 is in this way maintained out of engagement with the stud 66 the movement of the handle 38 even though it rocks the arm 56, will not be transmitted to the arm 63 and the shaft 12 will be maintained stationary during the accumulating, recording and other operations of the adding machine, and until the parts are restored to the normal positions shown in full lines in Figure 14 by a release of the key 61.

Having in view the foregoing it will be apparent that the machine hereinbefore described is a combined adding and counting machine, or the same may be used solely as an adding machine in all of the advantageous ways in which the latter machines are commonly employed.

As seen in the drawings, the counting wheels 213 of each counting device are held in fairly close frictional contact by means of spring plates or spiders 234 one of which is carried on the shaft 212 for each set of counting wheels. Thus while the wheels 213 are free to rotate independently of one another there is sufficient friction between the wheels and the shaft 212 to cause these parts to be rotated together when the shaft is unlocked and turned by means of the handle or knob 233 for the purpose of zeroizing the wheels of the counting devices by engaging the projections or stops 231 with the resetting plate 230.

Having thus described the invention, what is claimed is:

65. 1. The combination with an adding ma-

chine comprising accumulating mechanism and means for listing amounts accumulated by said mechanism, a keyboard including numeral keys for controlling the amounts accumulated in said accumulating mechanism, a main actuator for effecting operation of the accumulating device; of a plurality of counters each adapted for counting units of different values or denominations going to make up the various amounts accumulated and listed by the adding machine, selector means for said counters controlled by said keys, operating means for said counters associated with the main actuator, and means comprising a manipulative device on said key-board for preventing operation of the counters by the main actuator while permitting the normal adding operations.

2. The combination with an adding machine, comprising accumulating mechanism and means for listing amounts accumulated by said mechanism, a keyboard having mounted therein keys for setting up amounts to be accumulated and listed, a main actuator for effecting operation of the accumulating and listing devices; of a plurality of counters each adapted for counting units of different values or denominations going to make up the various amounts accumulated and listed by the adding machine, denomination counter selectors controlled by said keys, operating devices for said denomination counters adapted to be actuated by said main actuator when selected by said keys, and a key on said keyboard for preventing the movement of said operating devices by said main actuator.

3. The combination with an adding machine, comprising accumulating mechanism and means for listing amounts accumulated by said mechanism, a keyboard having mounted therein keys for setting up amounts to be accumulated and listed, a main actuator for effecting operation of the accumulating and listing devices; of a plurality of counters each adapted for counting units of different values or denominations going to make up the various amounts accumulated and listed by the adding machine, denomination counter selectors controlled by said keys, operating devices for said denomination counters adapted to be selected by said selectors, means for moving the operating devices thus selected including a shaft normally rocked by the main actuator, and optionally operable means for preventing the rocking of said shaft by the main actuator.

4. The combination with an adding machine, comprising accumulating mechanism and means for listing amounts accumulated by said mechanism, a keyboard having mounted therein keys for setting up amounts to be accumulated and listed, a main actu-

ator for effecting operation of the accumulating and listing devices; of a plurality of counters each adapted for counting units of different values or denominations going to make up the various amounts accumulated and listed by the adding machine, selector means for said denomination counters controlled by said keys, operating means for said denomination counters including a member normally operated by said main actuator, and a key on said keyboard operable at will for preventing the operation of said member by said main actuator.

5. The combination with an adding machine, comprising accumulating mechanism and means for listing amounts accumulated by said mechanism, a keyboard having mounted therein keys for setting up amounts

to be accumulated and listed, a main actuator for effecting operation of the accumulating and listing devices; of a plurality of counters each adapted for counting units of different values or denominations going to make up the various amounts accumulated and listed by the adding machine, selector mechanism for said denomination counters controlled by said keys and actuated by said main actuator, operating devices for said denomination counters adapted to be selected by said selectors, connections intermediate said operating devices and said main actuator including a pivoted latch, and optionally operable means for moving said latch to ineffective position.

In testimony whereof I affix my signature.
ALEXANDER E. SORUM.
